ELECTRIC WEFT DETECTING SYSTEM FOR
SHIFTING SHUTTLE BOX LOOMSRobert A. Donnan, Worcester, Mass., assignor to
Crompton & Knowles Loom Works, Worcester,
Mass., a corporation of Massachusetts

Application December 6, 1949, Serial No. 131,380

12 Claims. (Cl. 139—233)

1

This invention relates to electrical weft detecting systems more particularly for pick and pick looms having shifting shuttle boxes at each end thereof and it is the general object of the invention to provide such a system with simple electric circuits connected in such manner that each weft detector can be in but one of several branch detector circuits.

The invention relates more particularly to that type of weft detecting system wherein a gang of weft detectors is mounted in front of the shifting shuttle boxes at one end of the loom to rise and fall with them so that each weft detector is always in register with its shuttle box. Weft detection will ordinarily occur when the lay is on its front center position during the interval in the loom cycle in which the shuttle boxes can shift.

Looms of the type to which the invention relates are ordinarily provided with pattern chains which control shuttle box shifting levers or the like which move to shift a selected shuttle box to active position. The box shifting levers ordinarily start their motions at the beginning of the aforesaid box shifting interval when the lay is approximately at bottom center and continue moving throughout the interval until the lay reaches approximately top center position. The levers are therefore moving, if required to move, prior to the detecting period occurring when the lay is on front center.

It is an important object of the present invention to provide each detector with a branch detecting circuit connectable to an operating or control circuit by switch means which are positioned by the box shifting levers prior to the detecting period, thereby selecting the branch detecting circuit corresponding to the shuttle next to be active before the weft detectors have their detecting operations. This result is accomplished by switches which are moved by the box lifting levers to their selected positions early in the box shifting interval.

Certain weft detecting systems of the general type set forth herein have been used in the past but have had the defect that the weft detectors could be in series with each other so that if three of four shuttles being detected were depleted of weft the loom would be stopped despite the fact that the shuttle in action carried ample weft. It is another important object of the present invention to connect one side of each of the weft detecting circuits to a common wire in the system, thereby preventing the detectors from being in series with each other, and having the box shifting lever controlled switches so operated that only one detecting circuit can be completed through the operating circuit at the time of weft detection.

It is another object of the present invention to

5 operate the aforesaid switch means through friction devices associated with the box shifting levers in such manner that after the switches have been moved to their selected positions prior to detection by the detectors the box shifting levers can continue their motions to complete the shift of the shuttle boxes. The box shifting levers, being positively driven by the loom, are able to overcome the resistance offered by the friction devices whether moving to raise or effect lowering

10 of the shuttle boxes. If a box shifter lever remains in the same position for several picks the aforesaid friction devices might slip enough to open a contact. It is a further object of the invention to provide holding means positioned by the levers to prevent slipping of the friction devices.

15 With these and other objects in view which will appear as the description proceeds, the invention resides in the combination and arrangement of parts hereinafter described and set forth.

In the accompanying drawings, wherein a convenient embodiment of the invention is set forth,

20 Fig. 1 is a front elevation of the well-known Knowles head mechanism for operating the shuttle boxes in a fancy loom and showing the switches forming part of the invention,

Fig. 2 is an enlarged vertical section on line 2—2, Fig. 1.

25 Figs. 3 and 4 are diagrammatic views looking in the directions of arrows 3 and 4, respectively, Fig. 2.

Fig. 5 is a diagrammatic view in front elevation of the lay and shuttle boxes of a loom utilizing the invention showing a gang of electric weft detectors at the left end thereof,

30 Fig. 6 is a diagram of the electric circuits used with the invention,

Figs. 7 to 10 are diagrammatic views showing 35 the relative positions of the box shifting levers,

Figs. 11 to 14 represent four successive positions of the switch means controlled by the box shifting levers, and

40 Fig. 15 is an enlarged front elevation looking in the direction of arrow 15, Fig. 2, showing the holding means for one of the friction devices.

45 Referring particularly to Fig. 5, the loom lay 10 mounted on lay swords 11 is provided at its right end with a gang RG of shifting shuttle boxes mounted on the box lifter rod 12 and at its left end with another gang of shifting shuttle boxes LG having in the present instance four shuttle boxes I-IV mounted on a box lifter rod 13. The gang RG is moved vertically with respect to the lay by a box lifter chain 14 and in similar manner the left gang LG is moved by a box lifter chain 15.

50 The well known Knowles head mechanism K, which controls chains 14 and 15, includes upper and lower cylinder gears 20 and 21 between which

2

are located vibrator gears one of which is shown at 22. Gear 22 is mounted on a vibrator lever 23 the vertical position of which is determined by a pattern chain 24. Gear 22 operates a relatively short connector 25 attached to the upper end of a box lifter lever 26 the lower end of which is pivoted as at 27 for rocking movement with respect to the mechanism K. A longer connector 30 attached to and operated by a second vibrator gear 31 having its own vibrator lever is attached to the upper end of a box lifting lever 32 pivoted as at 33 intermediate its ends for rocking movement with respect to the mechanism K. The lower end of lever 32 has rotatably mounted thereon a sprocket 34.

Chain 15 for gang LG is attached as at 35 to lifter lever 26 and is trained around the sprocket 34 and then leads to the left over a guide pulley 36 and thence downwardly for connection to the box gang LG, see Fig. 1. The other chain 14 has similar operating levers and connections to position the gang RG, but these connections are omitted from the drawings.

Referring to the diagrammatic views 7-10, when the levers 26 and 32 are in the position shown in Fig. 7, the same as shown in Fig. 1, shuttle box I will be in the active position shown in Fig. 5. When lever 26 is rocked to the left while lever 32 remains unchanged, Fig. 8, box II will be in active position. When lever 26 is to the right and lever 32 is rocked to the position shown in Fig. 9, shuttle box III will be in active position, and when the two levers are in the positions indicated in Fig. 10 shuttle box IV will be in active position.

It is to be understood that the pattern chain 24 determines the vertical position of the vibrator gears 22 and 31 and therefore control the positions of the levers 26 and 32. Furthermore, levers 26 and 32 are each moved positively in both directions by their vibrator gears. The cylinder gears 20 and 21 are usually set so that they produce turning of the vibrator gears during a box shifting interval starting ordinarily when the lay 10 is on bottom center position and extending through the front center position thereof to the top center position, at which time the selected shuttle box will be in active picking position. The lay 10 swings backwardly and forwardly in usual manner, being on front center at a point in the loom cycle intermediate the start and finish of the box shifting interval.

The loom is provided with a detector carrier 40 which rises and falls with the shuttle box LG and has mounted thereon detectors D1-D4 which are of the electrical type. These detectors are so mounted that they detect the condition of weft in their respective shuttle boxes I-IV during a detecting period when the lay is at or near front center position, the carrier 40 shifting vertically but not partaking of the back and forth motion of the gang LG. The detectors D1-D4 may be considered collectively a detector gang DG the position of which is controlled by the pattern chain 24 in the same manner that the latter determines the vertical position of the gang LG.

The matter thus far described is of well-known construction and of itself forms no part of the present invention.

In carrying the present invention into effect provision is made for enabling the box lifter levers to select the detector of the gang DG corresponding to the shuttle box next to be in active position prior to the detecting period, and then

stopping the loom in the event that a selected detector indicates weft exhaustion.

In carrying the invention into effect I provide a support 45 secured as at 46 to some part of the loom frame, such as the arch 41. This plate has extending through the lower part thereof a pin 48 which is preferably held in fixed longitudinal position by a set screw 49 threaded into the lower part of support 45, see Fig. 2. The upper 10 left hand, or forward part of support 45 as viewed in Fig. 2 has secured thereto a block of insulating material 50 which has mounted thereon for movement relatively thereto flexible or resilient electric switch blades or prongs 51 and contacts 52 15 and 53. Pivotedly mounted on pin 48 is a switch operating lever 55 attached by a connector rod 56 to lever 32, as at 57. When lever 32 rocks back and forth lever 55 rocks with it. A flat plate 60 made preferably of insulating friction material, such as hard fiber, is located between arm or lever 55 and a washer 61 secured to support 45. A compression spring 62 interposed between a collar 63 on pin 48 and lever 55 urges the latter and plate 60 against the washer 61. A pin 65 secured to lever 55 extends through a slot 66 in plate 60, see Fig. 15.

Lever 55 will be in the full line position shown in Fig. 3 when either of shuttle boxes I or II is active, and the upper part or operating arm 30 70 of friction plate 60 will be to the right to connect one of the two electrically connected prongs 51 with contact 52. Motion of arm 70 to the right is limited by a stop pin 71 on support 45 passing through a hole 72 in arm 70 having a 35 diameter much larger than that of pin 71. Arm 70 moves from the full line position to the dotted line position, Fig. 3, when either of shuttle boxes III or IV is to be active, and connects one of the prongs 51 with contact 53. Stop pin 71 also 40 limits motion of arm 70 to the left. The electrical connection of one or the other of prongs 51 with contact 52 or 53 occurs during the first part of the rocking of lever 32 before the lay reaches front center position and before the weft detectors can perform their weft detecting operations. Thereafter the friction plate 60 slips relatively to lever 55 to permit continued motion of lever 32 to complete shifting of gang LG.

If lever 32 should remain in the position 50 shown in Fig. 1 for several picks there would be the possibility that friction plate 60 might slip enough relatively to lever 55 to permit right hand prong 51, Fig. 3, to move away from contact 52. In order to prevent this slipping pin 55 will be moved to the left end of slot 66 in friction plate 60 when lever 32 moves to the position shown in Fig. 1, and since it is a characteristic of the Knowles head that the box lifter levers are locked by action of the corresponding 60 vibrator lever, vibrator gear and connector, friction plate 60 will also be locked by pin 65 against movement toward a neutral position in which prong means 51 would be out of engagement with contact 52. Lock pin 65 will be at the 65 right end of slot 66 when lever 55 has been moved to the dotted line position, Fig. 3, thereby preventing slipping of plate 60 toward a neutral position.

Support 45 has secured to the back thereof a 70 second block 75 of insulation which supports resilient prong members 76 and 77 mechanically connected together by an insulating collar 78. These prong members are for engagement respectively with contacts 79 and 80. Other prong members 81 and 82 mechanically connected to-

gether by an insulating collar 83 are adapted for engagement with contacts 84 and 85, respectively. Prong members 76 and 81 are electrically connected together, as by connector 86, Fig. 4, to form in effect a single prong designated diagrammatically at P1 in Fig. 6, while the prong members 77 and 82 are electrically connected by connector 87 to form in effect a single prong member designated diagrammatically at P2 in Fig. 6.

The prong members shown in Fig. 4 have their positions determined by lever 90 rockably mounted on the rear part of pin 48, see Fig. 2, and positioned by a connector rod 91 attached as at 92 to the box lifter lever 26. A friction plate 93 of insulation material similar to plate 60 is located between lever 90 and washer 94 secured to support 45, and a compression spring 95 similar to spring 62 is interposed between lever 90 and collar 96 on pin 48. The construction and operation of plate 93 and lever 90 is similar to the construction and operation already described in connection with the previous description of lever 55 and plate 60. An upwardly extending arm 97 of plate 93 is formed with a hole 98 through which the rear part of stop pin 71 extends. A pin 99 on lever 90 extends through a slot 100 in friction plate 93 similar to slot 66 in plate 60 and for the same purpose.

When lever 90 is in the position shown in full lines in Fig. 4 prong members 76 and 77, corresponding respectively to prong elements P1 and P2, Fig. 6, are electrically connected to contacts 79 and 80, respectively. When box lever 26 shifts arm 97 moves to the left to the dotted line position thereof to cause contact members 81 and 82, corresponding also to prongs P1 and P2, respectively, Fig. 6, to engage contacts 84 and 85, respectively, at the same time enabling contacts 79 and 80 to be disengaged from their corresponding prong members.

The shift of arm 97 from the full line to the dotted line position shown in Fig. 4 occurs during the first part of the box shifting interval and is completed before the lay reaches front center, the lever 90 thereafter sliding with respect to plate 93.

It will thus be seen that the shift in position of the switches shown in Figs. 3 and 4, when they occur, will occur prior to the time in a box shifting interval when the weft detectors detect the condition of weft in the shuttle boxes I-IV. These switches, shown at 51, P1 and P2 in Fig. 6, are collectively designated as switch means S.

Referring particularly to Fig. 6, the electric circuit means used with the invention includes a transformer T, a solenoid 101 which when energized either effects immediate stoppage of the loom, or sets mechanism not shown herein but well understood to effect loom stoppage, and preferably though not necessarily a relay 102 controlled by the weft detectors and effective when energized to cause energization of the solenoid.

The electric weft detectors are each made with two detecting fingers 105 and 106 mounted in a base 107 made of electric insulation material. Each pair of fingers is adapted for engagement with a ferrule 108 of a bobbin being detected if the bobbin is depleted of weft. When ample weft is present the ferrule will be covered and the two fingers 105 and 106 will be kept insulated from each other during the detecting period. When exhaustion of weft occurs in any

of the shuttle boxes the detector fingers of the corresponding detector will be electrically connected by a ferrule 108.

As shown in Fig. 6, the right hand detector fingers 105 of the detectors D1-D4 are electrically connected by wires 111, 112, 113 and 114, respectively, to a grounded wire 110. The detector fingers 106 of the detectors D1-D4 are connected by wires 115, 116, 117 and 118, respectively, to contacts 79, 84, 80 and 85, respectively.

In describing the operation of the invention it may be assumed that gang LG has been in some position other than that shown in Fig. 5 and indication has been given by pattern chain 24 to move shuttle box I to active position. This indication will be followed by such movements of one or the other, or both, of the two box levers 26 which will move them to the positions shown in Figs. 1 and 7, but before such movement is completed the prongs 51 and P1 and P2 will be in the position shown in Fig. 6 prior to the weft detecting period, and switch means S will be as shown in Fig. 11. If, as the lay beats up, weft is depleted in shuttle box I the following circuit will be completed: transformer T, wire 120, shipper handle control switch SS, wire 121, relay 102, wire 122, prong or switch 51, contact 52, prong or switch P1, contact 79, wire 115, detector finger 106, uncovered ferrule 108 in shuttle box I, detector finger 105, wire 111, wire 110 to the ground, and up from the ground through wire 123 back to the other side of the transformer. When this circuit is completed the relay is energized and electric conducting armatures 125 and 126 of the relay will move to the left from the position shown in Fig. 6, whereupon a holding circuit is established through the relay as follows: From the transformer through the relay to wire 122, contact 127, armature 125, and wire 128 to ground. When this circuit is established the relay is maintained energized and is thereafter independent of detector D1.

At the same time that the holding circuit is closed armature 126 engages contact 130, whereupon the solenoid circuit will be closed and current will flow from the transformer to wire 121, through wire 131, solenoid 101, wire 132, armature 126, contact 130, and wire 133 to the ground. This establishes conditions which bring about stoppage of the loom and opening of the shipper handle control switch SS, the opening of which breaks the holding circuit to deenergize the relay and permit the armatures 125 and 126 to return to their normal positions shown in Fig. 6.

It will be apparent from Fig. 6 that when detector D1 is in the selected branch detecting circuit the other detectors will be disconnected from switch 51 and they will not be able to give indication of weft exhaustion even though they should engage uncovered ferrules 108 in their respective shuttle boxes. It will also be apparent that since the detectors all have one of their detecting fingers connected to the wire 110 it is not possible for them to become connected in a series circuit to give a false indication and effect unnecessary loom stoppage.

If shuttle box II is to move to active position the prongs P1 and P2 will be shifted to engage contacts 84 and 85, see Fig. 12, respectively, but there will be no shift of prong 51, hence the lowest detector D4 cannot be connected to wire 122.

If shuttle box III is to be active prong 51

will shift into engagement with contact 53, see Fig. 13, thereby preventing connection of either the detectors D1 or D2 with wire 122, and the prongs P1 and P2 will be in the position shown in Fig. 6 so that the detector contact 80 corresponding to detector D3 will be electrically connected to prong P1 and thence through prong 51 to the wire 122. Also, if shuttle box IV is active a circuit will be completed through detector D4, contact 85, prong P2, contact 53 and prong 51. In no instance will it be possible to have more than one detector connectible to wire 122 at a time.

The prongs 51, P1 and P2, being moved to positions corresponding to the next shuttle box to be active prior to the detecting period, permits the use of the relatively simple circuit shown in Fig. 6, without the use of holding relays or other electrical equipment, because of the fact that the prongs forming part of the switch mechanism S move to positions corresponding to the shuttle box next to be active prior to the detecting period.

Fig. 6 shows both a solenoid and a relay, but it is to be understood that the invention is not necessarily limited in its use to a relay, inasmuch as the relay can be replaced by the solenoid, and a holding circuit used or omitted, as desired.

From the foregoing it will be seen that the invention sets forth simple electric means by which the box shifting levers 26 and 32 act during the first half of a box shifting interval to move, or maintain, the prongs 51, P1 and P2 in positions corresponding to the detector associated with the shuttle box next to be active before weft detection occurs. In order to assure retention of the prongs or prong members shown in Figs. 3 and 4 in their selected position, the compression springs 62 and 95 may be made as strong as desired and there will be ample power derivable from the positively moved box shifting levers 26 and 32 to overcome any frictional resistance to movement of levers 55 and 86 with respect to their friction plates. The friction plates 60 and 93 and their springs 62 and 92 constitute yielding means or connections operatively relating the box lifter levers to the switch means and enable the lifter levers during the first part of their movements which shift the shuttle boxes to move the switches. The prongs P1 and P2 cooperate with two pairs of detector contacts one of these pairs comprising contacts 79 and 84 associated with the upper pair of detectors, Fig. 6, while switch P2 is associated with detector contacts 80 and 85 for the lower pair of detectors. The prongs P1 and P2 are capable of engagement with but one contact of each pair of detector contacts at a time, and the prong 51 is engageable with but one of the contacts 52 or 53 at a time to determine which pair of detector contacts shall be capable of completing the circuit. Furthermore, the pins 65 and 99 hold the friction plates 60 and 93 from moving away from their selected positions due to vibration of the loom should the box shifting levers remain stationary for several successive picks of the loom. The primary blade 51 and its primary contacts 52 and 53 may be considered a primary selector switch means or control PC positioned by box lever 32, and the secondary blades P1 and P2 and their secondary contacts 79, 80, 84 and 85 may be considered a secondary selector switch means or control SC positioned by box lever

26, see Fig. 6. The two switch means PC and SC collectively form the previously mentioned selector switch means S.

Having thus described the invention it will be seen that changes and modifications of the foregoing specific disclosure may be made without departing from the spirit and scope of the invention.

What is claimed as new is:

1. In an electric weft detecting system for a loom having a lay provided with a gang of four shuttle boxes which move relatively to the lay during a box shifting interval, mechanism controlling the movements of said gang during said interval including two levers which by their movements determine which shuttle box of the gang shall be in active position at the end of a shifting interval, an electric weft detector having two electrodes for each shuttle box performing a detecting operation during a detecting period occurring during a box shifting interval, electric circuit means effective when closed to cause loom stoppage including one of the electrodes of each detector, said one electrodes being connected to the circuit means in parallel, selector electric switch means, and yielding connections operatively relating the selector switch means to said levers by which the latter move the switch means during the first part only of said movements of the levers to electrically connect the other electrode of the detector corresponding to the shuttle box to be in active position at the end of a box shifting interval to said circuit means prior to the detecting period occurring in said interval, the detector corresponding to the shuttle box to be in active position, if indicating weft exhaustion, closing said circuit means during the detecting period.
2. In an electric weft detecting system for a loom having a lay provided with a gang of shuttle boxes which move relatively to the lay during a box shifting interval, mechanism controlling the movements of said gang during said interval including two levers each having movements to two positions and determining which shuttle box of the gang shall be in active position at the end of a shifting interval, an electric weft detector for each shuttle box detecting weft in the latter during a detecting period occurring between the start and finish of each shifting interval, provided a weft supply is in the corresponding shuttle box, each detector having two electrodes, electric circuit means including a common conductor effective when closed to cause loom stoppage, one electrode of each detector being connected to said common conductor, a selector contact for each detector, each selector contact being electrically connected to the other electrode of the corresponding detector, selector switch means, and yielding means operatively connecting the selector switch means to said levers causing the latter during the first part only of said movements thereof to move the selector switch means prior to a detecting period to electrically connect to said circuit means the selector contact corresponding to the shuttle box to be in active position at the end of the shifting interval during which the detecting period occurs, said circuit means being closed during the detecting period, provided the detector corresponding to the shuttle box to be in active position at the end of the shifting interval indicates weft exhaustion.

3. In an electric weft detecting system for a loom having a lay provided with a gang of four shuttle boxes which move relatively to the lay during a box shifting interval, mechanism controlling the movements of said gang during said intervals including two levers each movable to two positions and determining which shuttle box of the gang shall be in active position at the end of a box shifting interval, an electric weft detector for each shuttle box having two electrodes, the detectors capable of indicating weft exhaustion during a detecting period occurring during a box shifting interval, electric circuit means including a common conductor effective when closed to cause a change in loom operation, one electrode of each detector being connected to said common conductor, two primary selector contacts corresponding to one of said levers, four secondary selector contacts corresponding to the other lever, one secondary contact for each shuttle box connected electrically to the other electrode of the corresponding detector, and primary and secondary electric switch means controlled by said one lever and by said other lever, respectively, electrically connecting the secondary contact corresponding to the shuttle box to be in active position at the end of a shifting interval to said circuit means through a primary contact prior to the detecting period, the detector corresponding to the shuttle box next to be in active position, if indicating weft exhaustion, closing said circuit means.

4. In an electric weft detecting system for a loom having a lay provided with a gang of shuttle boxes which move relatively to the lay during a box shifting interval starting when the lay is approximately on bottom center and ending when the lay is approximately on top center, mechanism controlling the movements of said gang during said interval and including two levers each movable to two positions and determining which shuttle box of the gang shall be in active position at the end of a box shifting interval, an electric weft detector for each shuttle box having two electrodes, each detector capable of having a detecting operation during a detecting period occurring when the lay is substantially on front center, electric circuit means effective when closed to cause loom stoppage including one of the electrodes of each detector, said one electrodes being connected in parallel to the circuit means, a selector contact for each detector electrically connected to the other electrode of the detector, selector electric switch means, and yielding means operatively connecting the selector switch means to said levers causing the latter to move said selector switch means between a bottom center position of the lay and the detecting period of a box shifting interval to connect to said circuit means the selector contact corresponding to the shuttle box to be in active position at the end of the box shifting interval, the detector corresponding to said shuttle box to be in active position, if indicating weft exhaustion during the detecting period, closing said electric circuit means through the selector contact corresponding to said shuttle box to be in active position.

5. In an electric weft detecting system for a loom having a lay provided with a gang of four shuttle boxes which move relatively to the lay during a box shifting interval, mechanism controlling the movements of said gang during said

box shifting interval including two levers each movable during a box shifting interval to two positions to move the gang and determining which shuttle box of the gang shall be in active position at the end of a shifting interval, an electric weft detector having two electrodes for each shuttle box capable of indicating weft exhaustion in the corresponding shuttle box during a detecting period occurring subsequent to the start of each box shifting interval, provided a weft supply is in the corresponding shuttle box, electric circuit means effective when closed to cause a change in loom operation and including one of the electrodes of each of the detectors, the latter electrodes being connected to said circuit means in parallel, primary electric switch means operated by one of said levers and including two primary selector contacts, secondary selector switch means operated by the other lever including four secondary selector contacts, one for each shuttle box and the corresponding detector, each secondary contact being electrically connected to the other electrode of the corresponding detector, and means operated by said levers electrically connecting the secondary selector contact corresponding to the shuttle box to be in active position at the end of a shifting interval to said electric circuit means through one or the other of said primary contacts prior to the detecting period of the box shifting interval, whereby the detector corresponding to the shuttle box to be in active position at the end of the interval, if indicating weft exhaustion, closes said electric circuit means.

6. In an electric weft detecting system for a loom having a lay provided with a gang of shuttle boxes which move with respect to the lay during a box shifting interval, mechanism including two box lifter levers having movements during a box shifting interval to move said gang relatively to the lay and determine which shuttle box shall be in active position at the end of a shifting interval, electric circuit means effective when closed to cause loom stoppage, the circuit means including branch detector circuits connected in parallel thereto, one branch circuit for each shuttle box, an electric weft detector having two electrodes for each shuttle box and branch circuit capable of having a detecting operation during a detecting period occurring during each box shifting interval, each branch detector circuit including the electrodes of the associated detector and a selector contact, selector electric switch means, and yielding means operatively connecting the selector switch means to said levers and effective during the first part of said movements of the latter to cause said levers to move the selector switch means during a box shifting interval prior to the corresponding detecting period to connect to said electric circuit means the selector contact and associated branch detector circuit corresponding to the shuttle box to be in active position at the end of the shifting interval, the detector corresponding to the shuttle box to be in active position, if indicating weft exhaustion, completing said electric circuit means.

7. In an electric weft detecting system for a loom having a lay provided with a gang of shuttle boxes movable relatively to the lay during a box shifting interval, mechanism including levers operatively connected to said gang and movable during a box shifting interval to

move the gang relatively to the lay and determine which shuttle box shall be in active position at the end of a shifting interval, an electric weft detector having two electrodes for each shuttle box capable of having a detecting operation relative to the associated shuttle box during a detecting period occurring after the start of a box shifting interval, electric circuit means effective upon closure to stop the loom, the circuit means including one of the electrodes of each detector, selector contacts, one for each detector, connected electrically to the other electrode of the corresponding detector, selector electric switch means including a switch for each lever, and operative connections between each lever and the corresponding switch means effective during a shifting interval prior to the detecting period corresponding thereto to connect the selector contact corresponding to the shuttle box to be in active position at the end of the shifting interval to said circuit means, to the end that the electric weft detector corresponding to the shuttle to be in active position at the end of a shifting interval, if indicating weft exhaustion, will close said electric circuit means.

8. In an electric weft detecting system for a loom having a lay provided with a gang of four shuttle boxes which move relatively to the lay during a box shifting interval, mechanism including two levers operatively connected to said gang movable during a box shifting interval to move the gang relatively to the lay, the levers by the positions thereof at the end of a box shifting interval determining which shuttle box of the gang shall be in active position, an electric weft detector having two electrodes for each shuttle box capable of having a detecting operation in the corresponding shuttle box during a detecting period occurring after the start of a box shifting interval, electric circuit means effective when closed to stop the loom, one of the electrodes of each detector being connected to said electric circuit means, a pair of primary selector contacts, primary electric switch means to connect either of said primary contacts to said electric circuit means, four secondary selector contacts, one for each detector electrically connected to the other electrode of the corresponding detector, secondary electric switch means including two blades, one blade capable of connecting one primary contact to either of two secondary contacts and the other blade capable of connecting the other primary contact to either of the other two secondary contacts, and operative connections between one of said levers and the primary switch and other operative connections between the other lever and the secondary switch effective during a box shifting interval prior to the corresponding detecting period to connect the secondary selector contact corresponding to the shuttle box to be in active position at the end of the box shifting interval to the primary selector contact corresponding to the shuttle box to be in said active position, to the end that the electric weft detector corresponding to said shuttle box to be in active position, if indicating weft exhaustion, will complete said electric circuit means through the secondary and primary contacts corresponding to said shuttle box to be in active position.

9. In an electric weft detecting system for a loom having a lay provided with a gang of four shifting shuttle boxes movable relatively

thereto during a box shifting interval, mechanism including two levers each capable of being moved positively to either of two positions by said mechanism throughout a box shifting interval, said levers effecting shifting of the shuttle boxes and determining which of the latter shall be in active position at the end of a box shifting interval, an electric weft detector having two electrodes for each shuttle box capable of indicating weft exhaustion during a detecting period occurring in each shifting interval, electric circuit means effective when closed to cause a change in loom operation, one electrode for each detector being permanently connected to said electric circuit means, primary selector switch means including two primary selector contacts, secondary selector switch means including four secondary selector contacts, one secondary contact electrically connected to the other electrode of each detector, friction operative connections between one of said levers and the primary selector switch means, and other friction operative connections between the other lever and the secondary selector switch means, 25 said friction operative connections effective to cause said levers when moving during the first part of a box shifting interval to connect a primary selector contact and a secondary selector contact corresponding to the shuttle box 30 to be in active position at the end of the shifting interval to said electric circuit means prior to said detecting period, said levers continuing to move during the remainder of the box shifting interval subsequent to the detecting 35 period and said friction operative connections yielding to permit said continued movement of the levers, whereby the electric weft detector corresponding to the shuttle box in the active position at the end of a shifting interval, if indicating weft exhaustion, completes said electric circuit means.

10. In an electric weft detecting system for a loom having a lay provided with two shuttle boxes movable relatively thereto during a box 45 shifting interval starting before and continuing after the lay reaches front center position in the loom cycle, shuttle box shifting mechanism including a box lifter lever operatively connected to the shuttle boxes and determining which of the latter is to be in active position at the end of a shifting interval, electric weft detecting means including a detector for each shuttle box performing a detecting operation when the lay is substantially on front center, electric circuit 55 means effective when closed to cause a change in loom operation and including the detector means and selector electric contacts, one for each shuttle box, the open and closed condition of which is to be determined prior to the time 60 the lay reaches front center during a box shifting interval, a contact controlling lever operatively connected to the box lifter lever and moved by the latter throughout a box shifting interval, friction means controlling the opening and 65 closing of said contacts frictionally engaging the operating lever but capable of slipping relatively thereto, and stop means for the friction means, the box lifter lever when shifting during a box shifting interval moving the contact controlling lever and causing the latter by reason of frictional engagement with the friction means to determine the open and closed condition of the contacts prior to the time the lay reaches front 70 center, the stop means arresting further movement of the friction means and the operating

lever continuing to move during the remainder of the shifting interval and slip relatively to the friction means.

11. In an electrical weft detecting system for a loom having two shuttle boxes movable relatively to the lay during a box shifting interval starting before and continuing after the lay is on front center position in the loom cycle, mechanism including a box lifter lever effecting shifting of the shuttle boxes during said interval and moving throughout the latter and determining which shuttle box shall be in active position at the end of said interval, electric switch means including two contacts, one for each shuttle box, the open and closed condition of which is to be determined for any shifting interval prior to the time the lay reaches front center in the interval, a switch operating lever operatively connected to the lifter lever, and electric switch closing means operatively connected frictionally to the operating lever and effective during a part of the box shifting interval prior to the time the lay is on front center to close the contact corresponding to the shuttle box to be in active position at the end of the interval and thereafter slip relatively to the operating lever as the latter continues to move during the remainder of the box shifting interval.

12. In an electrical weft detecting system for a loom having two shuttle boxes movable relatively to the lay during a box shifting interval in the loom cycle, a box lifter lever moving during

the interval operatively connected to the shuttle boxes and moving throughout said interval to shift the shuttle boxes relatively to the lay, a support fixed with respect to the loom, a pair of spaced electric contacts on said support insulated therefrom, one for each shuttle box, the open and closed condition of said contacts for any given shifting interval to be determined during the interval prior to the time the lay reaches front center, an operating lever pivoted on said support operatively connected to the lifter lever and moved by the latter throughout the box shifting interval, and a friction plate frictionally engaging the operating lever and moved by the latter to close the contact corresponding to the shuttle box to be in active position at the end of the interval during that part of the box shifting interval prior to the time the lay is on front center and slipping relatively to the operating lever during the remainder of the shifting interval.
